(57) **CLAIM**

The ornamental design for a privacy screen, as shown and described.

DESCRIPTION

FIG. 1 is a front view of the privacy screen of the instant invention;

FIG. 2 is a right side view thereof;

FIG. 3 is a left side view thereof;

FIG. 4 is a top view thereof;

FIG. 5 is a bottom view thereof; and,

FIG. 6 is a perspective environmental view thereof illustrating the privacy screen in combination with other privacy screens. The portions of the Figures shown in broken lines are for illustrative purposes only and form no part of the claimed design.
